CLAIM

The ornamental design for a putter grip, as shown and described.

DESCRIPTION

FIG. 1 is a perspective view of a putter grip;
 FIG. 2 is a front view of the putter grip;
 FIG. 3 is a rear view of the putter grip;
 FIG. 4 is a right side view of the putter grip;
 FIG. 5 is a left side view of the putter grip;
 FIG. 6 is a top view of the putter grip; and,
 FIG. 7 is a bottom view of the putter grip.

The broken lines shown are for the purpose of illustrating the tip and the cap of the putter grip and form no part of the claimed design.

1 Claim, 2 Drawing Sheets(56)
